UNITED STATES PATENT OFFICE

150,041

DESIGN FOR A TYPEWRITER OR THE LIKE

John C. Veltman and William O. Michelsen, St. Louis County, Mo., assignors to The Emerson Electric Manufacturing Company, St. Louis, Mo., a corporation of Missouri

Application September 23, 1946, Serial No. 133,528

Term of patent 14 years

(Cl. D64—11)

To all whom it may concern:

Be it known that the undersigned, John C. Veltman and William O. Michelsen, both citizens of the United States, residing in the county of St. Louis, State of Missouri, have invented a new, original, and ornamental Design for a Typewriter or the like, of which the following is a specification, reference being had to the accompanying drawing, forming a part thereof, in which:

Fig. 1 is an isometric view of a typewriter, or the like, embodying our new design; and

Fig. 2 is a rear elevational view thereof.

Characteristic features of our new design for typewriters, or the like, reside in the blending mask base, mask cover, and paper shelf, all three of which are stippled to bring out the smooth

curves, and in the continuity of lines of the space bar and adjacent mask base.

We claim:

The ornamental design for a typewriter or the like, substantially as shown and described.

JOHN C. VELTMAN.

WILLIAM O. MICHELSSEN.
